UNITED STATES PATENT OFFICE.

JOHN WEIBLE AND FOREST LOHR, OF STOYESTOWN, PENNSYLVANIA.

DESIGN FOR A PHONOGRAPH-CABINET.

54,489.

Specification for Design.

Patented Feb. 10, 1920.

Application filed June 18, 1919. Serial No. 305,184. Term of patent 7 years.

To all whom it may concern:

Be it known that we, JOHN WEIBLE and FOREST LOHR, citizens of the United States of America, residing at Stoyestown, in the county of Somerset and State of Pennsylvania, have invented a new, original, and ornamental Design for a Phonograph-Cabinet, of which the following is a specification, reference being had to the accompanying drawing, forming part hereof.

The figure is a perspective view of a phonograph cabinet, showing our new design.

We claim:

The ornamental design for a phonograph cabinet, as shown.

JOHN WEIBLE. [L. S.]
FOREST LOHR. [L. S.]
